UNITED STATES PATENT OFFICE.

FRANK H. BRADSHAW, OF RENO, NEVADA.

WRENCH.

Application filed June 22, 1925. Serial No. 38,739.

This invention relates to improvements in wrenches and particularly represents a continuation in part of my present pending application, Serial No. 704,965, filed 5 April 8th, 1924.

The principal objects of my invention are to provide a wrench whose jaws may be very quickly adjusted to any desired setting, and when applied to the work will 10 remain automatically locked in engagement with the object; one which may be operated by a ratchet handle or by means of an ordinary brace; one which may be used as a chuck or handle for small tools of different kinds, as well as for a wrench; and one whose jaws are so constructed that they 15 may be used as an adjustable reamer.

The wrench is also of such form that it may be used either as a flat wrench, or disposed 20 on a nut and the like in the same manner as a socket wrench. My wrench is therefore particularly suitable to be used where the nut itself is some distance from the operator and in a place inaccessible to 25 the hand or an ordinary wrench.

A further object of the invention is to produce a simple and inexpensive device and yet one which will be exceedingly effective for the purpose for which it is 30 designed.

These objects I accomplish by means of such structure and relative arrangement of parts as will fully appear by a perusal of the following specification and claims.

35 In the drawings similar characters of reference indicate corresponding parts in the several views:

Fig. 1 is a side elevation of my improved wrench.

40 Fig. 2 is a vertical section of the same.

Fig. 3 is a cross section on the line 3—3 of Fig. 1.

Fig. 4 is a bottom plan view of one of the jaws.

45 Referring now more particularly to the characters of reference on the drawings, the numeral 1 denotes the body of the wrench preferably of cylindrical form, having at one end a reduced centrally located shank 2 which is provided at its extremity 50 with a square tapered portion 3 to receive the jaws of an ordinary brace.

55 Projecting diagonally through the body from one end to the other in opposed and side by side relation are channels 4. These channels slidably receive, with a snug run-

ning fit, the shank 5 of jaws 6, which are provided on one end of said shanks. The jaws are symmetrical and are so disposed relative to the shanks that while the latter 60 are in offset alignment transversely of the body, the jaws are located in direct opposed alignment with each other and centrally with respect to the body. The adjacent faces of the jaws are parallel to 65 each other and to the axis of the body, while the outer faces are convexly curved and symmetrically tapered in a direction opposite to the slant of their shanks. Such outer faces are provided with longitudinal 70 grooves or corrugations 7 to form reaming members, while the adjacent faces of the jaws are vertically grooved as at 8 of such form as to receive the usual tapered shank of a bit etc.

75 The body 1 between the ends of the channels is provided with a row of circumferentially spaced recesses 9, surrounding the body between the portions of the shanks which project outwardly of the body, and guided against longitudinal displacement thereby, is a ring 10, which is mounted in connection with a handle 11 projecting radially therefrom. Opposed pawls 12 adapted to enter the recesses 9 are 80 mounted in connection with the ring and handle. A control sleeve 13 is turnably mounted on the handle and engages the inner ends of the pawls. This operates the same as an ordinary ratchet brace, to 85 cause either pawl to be engaged or disengaged with the recesses, depending on whether the body is to turn with a right or left hand movement of the handle.

In operation it will be seen that if the 90 shanks are moved up or down or in or out of the body, the jaws will be correspondingly moved to or from each other. This, as will be evident, will alter the span between the jaws and enable different sized nuts or 100 bolt-heads to be engaged thereby.

To apply the jaws to a nut they are preferably first spread to clear the same in any suitable manner, and are then placed over the nut with the points or outer ends of the 105 jaws resting on the surface surrounding the nut. The body is then pressed toward the jaws, a light oscillatory movement in a lateral plane being imparted to the body at the same time. This will cause the jaws to be 110 moved toward each other, until they firmly engage the nut.

The shanks will then automatically lock in the body against further movement, causing the jaws to engage the nut with a vise-like grip and enabling said nut or other member to then be carried with the wrench without slipping. If the body is then rotated either by means of the handle or through the medium of a brace applied to the member 3, the nut or bolt will of course 10 be rotated likewise. The shanks crossing each other intermediate the ends of the body, the intermediate metal of said body beyond and between the shanks on both sides of the intersection, enables the body to have the necessary strength to resist fracture when turning or torsional pressure is applied to the tool.

If the use of the handle is not desired the shanks are depressed into the body until 20 their outer ends are clear of the sides of said body. The ring 10 may then be slipped upwardly and off the body, together of course with the handle and pawls which form a unitary structure with said ring.

If the tool is to be used for reaming purposes a nut or other rigid object is forced between the jaws, the width of said object being such as will give the desired diameter between the outer faces of the jaws. The 30 jaws are then inserted into the orifice to be reamed, and the body is rotated in one manner or the other, as above described.

It will be seen from Fig. 4 particularly that the jaws, and especially their adjacent or operating faces, are disposed in a transverse plane not at right angles to the longitudinal plane of their shanks.

This gives a more even balance of the jaws and assists the frictional lock of the 40 shanks in the channels.

From the foregoing description it will be readily seen that I have produced such a de-

vice as substantially fulfills the objects of the invention as set forth herein.

While this specification sets forth in detail the present and preferred construction of the device, still in practice such deviations from such detail may be resorted to as do not form a departure from the spirit of the invention, as defined by the appended 45 claims.

Having thus described my invention what I claim as new and useful and desire to secure by Letters Patent is:

1. A wrench comprising a body, opposed and cooperating jaws adjustably mounted therein, handle means for turning the body removably applied thereto, and means formed integral with the jaws for normally retaining the handle means against removal. 50

2. A wrench comprising a body, opposed and cooperating jaws adjustably mounted therein, handle means for turning the body removably applied thereto, said handle means including a ring turnable on the body, 55 and means provided with the jaws for normally retaining the ring against removal and guiding the same in its rotative movement.

3. A wrench comprising a body having 70 opposed diagonal channels therethrough disposed in transversely offset relation, shanks slideable through the channels and projecting beyond one end of the body, and transverse jaws on said projecting ends of 75 the shanks; the gripping faces of the jaws being parallel to each other but the transversely extending surfaces of said faces being disposed in planes other than at right angles to a plane parallel to the plane of 80 longitudinal movement of the shanks.

In testimony whereof I affix my signature.

FRANK H. BRADSHAW.
